BOAT

Carl H. Clement, Jr., United States Army,
Fort Belvoir, Va.

Application February 26, 1943, Serial No. 477,229.

12 Claims. (Cl. 9—6)

(Granted under the act of March 3, 1883, as
amended April 30, 1928; 370 O. G. 757.)

The invention described herein may be manufactured and used by or for the Government for governmental purposes, without payment to me of any royalty thereon.

This invention relates to a boat construction and more particularly to a small boat construction of the open type which is adapted to be wind or power driven and which has a wide bow and a bottom of shallow curvature.

The present invention is particularly adapted for usage in transporting persons or equipment onto a beach or other gradual shore where, owing to its bow shape in particular, the boat can be quickly unloaded. Such usage occurs frequently in military operations where landing on a hostile shore has to be accomplished. To this end, I have designed my boat to have a bottom construction which will carry the load required for such an operation and which will withstand stresses tending to distort it in either the fore and aft direction or in the transverse direction, while the hull is designed to permit fairly rapid travel to the objective and to permit rapid unloading of the boat when the objective is reached. Protection from waves, etc., is afforded by the sides of the boat which converge fairly sharply at the fore section to form a pointed bow.

Although landing barges, etc., are well known for military usage they do not have the lightness and speed necessary for certain types of operations particularly where a speedy craft is necessary and the total number of men required is not great. For such use it is desirable to have a boat which has certain of the advantages of a barge boat and certain of the advantages of a speed boat. I obtain these advantages in a single boat, which I designate by the name "storm boat," by designing the framework of the boat for strength and rigidity and by fitting the hull thereto so that the boat may be driven through the water at an appreciable rate of speed. The boat framework is formed of longitudinal members interlocked with transverse members to form a framework having a reticulated base portion which, viewed alone from above or below, is substantially rectangular from the stern to a transverse plane in the fore section of the boat. The bow framework is constructed to allow the hull to converge and form a pointed, but wide bow. The underside of the whole framework is curved but the curvature is slight, and the framework has a horizontal surface adapted to receive a floor member which, together with that portion of the framework included between it and the boat bottom forms, in effect, a box beam extending through-

out substantially the whole bottom of the boat. Such a construction provides a strong boat bottom which will not only support loads but which will support an outboard or inboard engine, or even a sail mast, and which will resist twisting strains tending to deform it whether such strains occur from waves, from the power source used, or from the load carried. Such a box beam construction provides means for dissipating torsional loads resulting from wave action or from any propelling means such as sails or mechanical power.

Lightweight materials are used throughout the boat and the hull is preferably formed of integral side, stern and bottom members. The transverse members of the framework have rib members extending upwardly at the sides of the boat to support the sides, and reinforcing battens are used throughout. Since the front portion of the hull is curved to a pointed bow, water resistance, tending to cut down on speed, is decreased.

Accordingly, it is an object of the present invention to provide a lightweight but strong wide-bow boat.

Another object of the present invention is to provide a boat having a framework affording resistance to torsional strain and a hull construction permitting rapid travel through the water.

Another object of the present invention is to provide a storm boat made of lightweight materials, the framework of which forms, together with the boat bottom and the floor on the inside of the boat, substantially a box-beam bottom construction which resists deformation, and the hull of which permits rapid travel through the water.

Another object of the present invention is to provide an open type storm boat having interlocked longitudinal and transverse members which form a framework having a reticulated base portion; a hull formed of integral side, stern and bottom members and an inner floor member, said members being assembled to form a substantially rigid structure having a wide pointed bow.

These and other objects of the present invention will become apparent from the following detailed description taken in conjunction with the accompanying drawings and the invention will be pointed out with particularity in the appended claims.

Fig. 1 is a perspective view of the boat showing the interior thereof;

Fig. 2 is a view of the boat framework, inverted, and looking down on the framework from the port side;

Fig. 3 is a cross-sectional view taken on line 55—3 of Fig. 1;

Fig. 4 is a perspective view, partially broken away, showing the construction of the joint connecting a frame member with the center stringer and the joint connecting this same frame member to the next adjacent stringer;

Fig. 5 is a sectional view, broken away, showing the chine construction;

Fig. 6 shows a modification of the construction disclosed in Fig. 5;

Fig. 7 is a diagrammatical sketch of the aft 10 port section showing the layout of the diagonal stiffener battens and their position relative to the stringers and frames.

Referring to the drawings, Fig. 1 shows the assembled boat. The hull portions shown include 15 side members 10, the stern plate or transom 11 with a cutaway portion 42a, and a portion of the bottom 12. The stern transom has attached thereto a support or mount 11a for mounting an outboard motor, if this is desired. The lower 20 interior of the boat is provided with a floor 13. A narrow deck 14 extends around the upper edge of the boat and attached adjacent thereto is a hand rail 15. The sides, stern and bottom members comprise the "boat shell" since they are 25 made of substantially thin integral members.

The framework proper is shown more completely in Fig. 2 but certain portions thereof appear in Fig. 1. These include the square frame members 16, "square" meaning at right angles 30 to the keelson, and the ribs 16a which form an integral part of the frames 16. Although the frames 16 are only partially shown in this figure, they are continuous, extending from gunwale to gunwale. Frames 16 are notched at 18 to receive 35 the continuous longitudinal battens 17, only one of which is shown in this figure. The bottom 12 and the sides 10 meet at chine 19 from which the ribs 16a extend to the gunwale as shown more clearly in Fig. 3. The joints between the ribs 16a and the sides 10 are reinforced by angular battens 20 which are glued in position and which may or may not be attached by screws. Most of the details described above are shown more clearly in Fig. 3.

Referring to Fig. 2, there is shown the assembled framework or skeleton with the sides, bottom and stern shell members removed. As shown, the framework comprises essentially square frame members 16, of which the ribs 16a are an integral part, continuous longitudinal stringers 21 and 22, chines 19, gunwales 23, and a prow member 24. Stringer 21 is the center stringer and has attached to the bottom side thereof, a keelson 25. Stringers 22 are the intermediate stringers and are adjacent to the center stringer 21. Between the intermediate stringers 22 and the chines 19, the continuous longitudinal battens 17 are located.

Except for those portions of the stringers 21 and 22 included between the two rearmost frames 16, the stringers are lightened by hollowed out portions 26 in stringer 21 and hollowed out portions 27 in stringers 22. These hollowed out portions 26 and 27, which might better be described as openings in the stringers, extend substantially from frame to frame except, as mentioned above, in the aft portion of the boat. Similarly, the frames 16 are lightened by hollowed out portions or openings 28 therein, such an opening being shown more clearly in Fig. 3. The portion of the framework just described, i. e., the frames and stringers, with the openings therein, when assembled in the manner shown in Fig. 2, produces the impression of a grill or network which I describe as a reticulated struc-

ture. Henceforth, when I refer to the reticulated portion of the boat framework, I intend to describe that portion formed by the square frames 16 which are interlocked with the stringers 21 and 22 to produce the network appearing structure shown in Fig. 2. This reticulated structure, as viewed from either above or below, produces a rectangular appearance since it extends from the stern to the fore portion of the boat, that is, to the second frame 16 from the prow 24, and is bounded by chines 19 which are substantially parallel up to this plane.

In addition to the main elements described above, Fig. 2 shows additional members which go to complete the framework. Thus, the center stringer 21 has formed thereon an extension 29 which is shaped to receive and support the prow or stem post 24. Prow 24 is, in turn, notched at 30 to receive the keelson 25 thus forming a smooth continuous member extending from the tip of the prow 24 to the stern. The frontmost frame 16 is reinforced by a solid curved member 31 which extends from chine to chine and which is attached to the member 29. This construction is further reinforced by a block 32 which is located at the joint between the extension 29 on stringer 21 and the frontmost frame 16. The intermediate stringers 22 have extensions 35 which extend from the end of the stringer to the joint between the frontmost frame 16 and chine 19. Extension members 35 are curved to conform to the taper of the hull. The bow framework construction just described is thus reinforced to withstand impact shocks and is shaped so that the bow of the hull may form a pointed structure. By the bow framework construction just described, the transition from the box-like framework which extends substantially from the stern to the bow to the pointed bow structure, is accomplished.

In the stern framework construction shown in Fig. 2, the numeral 36 indicates the solid portion of the center stringer 21 and the numerals 37 indicate the solid portion of the stringers 22. Solid portions 36 and 37 are provided with notched ends 38 which extend into the opening 28 in the rearmost frame 16. Reinforcing blocks 39 are attached to solid portions 36 and 37 and to the rearmost frame 16. Blocks 39 are glued into position and further held by screws 40 if so desired. The provision of solid portions 36 and 37 strengthens the stern and allows greater loading, a motor for example, at this point.

The cross-sectional detail of the boat, with 55 fastening screws omitted, is shown in Fig. 3. As shown there, the boat, in section, is substantially channel shaped since the sides 10 are substantially vertical and the bottom 12 is of slight curvature from the horizontal. Similarly, the square 60 frame members 16 and the integral rib portions 16a thereof are substantially channel shaped also. The curved portion of frame 16 follows the curvature of the bottom 12 since the latter is attached to the frame, and the inner floor 13 is attached to the horizontal portion of the frame. This construction, together with the stringers 21 and 22, forms the box beam structure referred to previously. Stern transom 11 is shown with cutaway portion 42a and bolts 43 hold motor 65 mount 11a in position.

The reinforcing elements for the frames and stringers are also shown in Fig. 3. Thus, angular corner battens 44 are located at the joints between the bottom 12 and the frames 16 and 75 stringers 21 and 22. At the intersection between

the stringers and frames, corner battens 45 are located. This intersection detail is shown more clearly in Fig. 4. Longitudinal battens 46 help support the floor 13.

The intersection detail of the joints between the frames and stringers, shown in Figs. 2 and 3, is shown more clearly in Fig. 4. As shown there, the stringers 21 and 22 are notched at 47 to receive the frame member 16. Notches 47 are deep enough to allow the portions of frame 16, which are received therein, to be flush with the edge surface of the stringers 21 and 22, as is shown in Fig. 4. In each corner of the joint thus formed, angular reinforcing battens 45 are placed which are glued and, if desired, screwed firmly into position. In the embodiment of my invention shown, these angular corner battens 45 are formed of wood although metal angle pieces could be used, if available, aluminum being a preferred metal for this purpose. The frame 16 is provided with a notch 48 which receives the keelson 25, not shown.

In the intersection detail just described, the provision of notches 47 in the longitudinal stringers to receive the square frames 16 permits rapid assembly of the framework since each of the frames is open in the center. The stringers can be turned sideways and slipped through the openings in the frames until they are in position, whereupon they can be righted and the frames secured into the notches in the stringer. The angular corner battens are then placed in position and fastened. While I use continuous stringers in the preferred embodiment of my invention, individual stringer sections could be utilized, such sections being joined to the frames by means of the angular corner battens shown in Fig. 4. The intersection detail also discloses the frame and stringer construction as being of plywood which may be either 3 or 5 ply, the latter being preferred. The reinforcing corner battens can be made of white oak or, if available, metal angle irons can be used.

Referring to Figs. 5 and 6, the details of the chine construction are shown. In Fig. 5, which is the preferred construction, the side member 10 and bottom 12 meet at chine 19. The bottom 12 is continuous from chine to chine, but it can be formed in two sections each extending from keelson to chine. As shown in Fig. 5, the bottom 12 and the side 10 are attached to chine 19 by screws 49. The bottom 12 is also attached to longitudinal batten 17 by screw members 49. At the joint between the bottom 12 and the side member 10, a strong water insoluble glue is used in addition to the fastening screws 49. In fact, all joints on the planking are screw fastened and glued.

The construction shown in Fig. 6 differs from that shown in Fig. 5 in that a bottom chine is formed at batten 17 in addition to the chine 19. As indicated there, the bottom member 12 is continuous from batten 17 on one side of the center stringer 21 to batten member 17 on the other side of center stringer 21, but, if desired, it can be formed in two sections each meeting at center stringer 21. Between the batten 17 and chine 19 an additional bottom member 50 is provided. Bottom members 12 and 50 and side members 10 are attached to the framework by means of fastening screws 49 and are additionally held in place by strong glue. The construction shown in Fig. 6 can be used where the curvature of the bottom 12 is less than that shown in Fig. 3 and it is desired to avoid a sharp bend at batten 17 to

bring the bottom into meeting engagement with the side members 10.

The diagrammatical layout shown in Fig. 7 discloses diagonal stiffener battens 51 which reinforce those portions of the bottom 12 included between the stringers and frames. Although these diagonal battens are not absolutely necessary, they contribute materially to the strength of the bottom member. Diagonal battens 51 are glued into position and may be additionally held by fastening screws, not shown.

In the construction described above, the various elements of the boat are made of wood, and I prefer to use plywood for the main elements because of the lightness and strength of this material and its adaptability to deformation for forming the hull or boat shell which covers the framework. The frames and stringers are preferably formed of 5 plywood and the hull of 3 plywood although this construction can be departed from if desirable. Although the stringers are continuous members in the preferred embodiment of my invention, they may be sectional members. The wooden blocks and corner batten members used in the boat are preferably formed of white oak pieces. In one construction of my boat I have employed a $\frac{3}{8}$ " white oak chine 19, an $\frac{1}{8}$ " x $1\frac{1}{8}$ " white oak batten 17, $\frac{5}{8}$ " white oak corner battens 44, an $\frac{1}{4}$ " x 2" white oak keelson 25 and $1\frac{1}{4}$ " white oak angles 45 at the intersection of the frames and stringers. These dimensions are merely illustrative and are intended in no way to limit the scope of my invention. In the assembly of the various elements of the boat, all joints are glued with a suitable shipbuilders' glue and all joints on the planking are screw fastened.

The interlocked stringer and frame construction described above, having on one side the boat bottom and on the other side the floor of the boat, gives the boat its rigidity and resistance to deformation. These elements, in conjunction, form essentially a box beam reinforced throughout and, in doing so, not only strengthen the boat but provide a convenient mount for either an outboard or inboard engine or even for the mast used to support a sail. The provision of such a base for the floor member also enables the boat to carry an appreciable load.

It will thus be seen that I have invented a wide-bow open boat which I refer to as a storm boat and which combines the desirable features of strength and speed, enabling it to reach an objective swiftly while carrying its load. The base portion of the boat is essentially rectangular in shape but is provided with a pointed bow to reduce water resistance. The rectangular portion of the boat gives rigidity, and the pointed portion aids in securing speed. The boat is easy to construct since it is made of lightweight materials, easily worked into shape and the provision of single pieces of plywood for the sides and bottom enable one to rapidly construct the hull by simply bending the plywood members into position and securing them. The boat is made mainly of wood and the only metal required is for fastening screws or, where desired, angle iron pieces for reinforcing joints.

While I have described and illustrated a particular embodiment of my invention, it is to be understood that I do not wish to be restricted thereto and that I intend to cover all modifications and improvements thereon which fall within the true spirit and scope of the appended claims.

Having thus described my invention, what I claim as new and wish to secure by Letters Patent is:

1. A boat comprising a plurality of transversely arranged frames provided with longitudinal openings substantially coextensive with the central portion of the frames, the openings in the respective frames being disposed in alignment, a plurality of longitudinal stringers projecting through said openings and interlocked with said frames to form a framework having a reticulated base portion, a boat bottom attached to the underside of the framework, a floor attached to the top side of the reticulated base portion of the framework, and boat shell side and stern members attached to the framework.

2. An open boat comprising a plurality of continuous gunwale to gunwale transversely arranged frames provided with elongated openings substantially coextensive with the central portion of the frames, the openings in the respective frames being disposed in alignment, rib members integral with said frames, boat shell side and stern portions supported by said rib members, said shell sides converging to form a pointed bow, a plurality of continuous longitudinal stringers projecting through said openings and interlocked with said frames to form a reticulated structure, a boat shell bottom portion attached to and covering the underside of said reticulated structure, and a floor attached to the top side of said reticulated structure.

3. A wide bow open boat comprising a plurality of transversely arranged frames, said frames having substantially vertical rib portions formed integral therewith and a substantially horizontal base portion having an elongated opening therein substantially coextensive with the central portion of the frames, the openings in the respective frames being disposed in alignment, a plurality of longitudinal stringers interlocked, within said openings, within the base portion of the frames to form a reticulated structure, a boat bottom attached to the underside of the reticulated structure, a floor attached to the top side of the reticulated structure and integral side and stern shell members attached to the frame ribs.

4. A wide bow open type boat comprising a plurality of substantially channel-shaped frames provided with longitudinal openings substantially coextensive with the central portion of the frames, the openings in the respective frames being disposed in alignment, rib members formed integral with said frames and forming the sides of said channel, a plurality of longitudinal stringers projecting through said openings and interlocked with the base portions of said channel shaped frame members to form a reticulated structure, said reticulated structure extending from the stern to a plane adjacent the bow, integral side, stern, and bottom shell members, and a floor member supported by and attached to the top surface of the reticulated structure.

5. An open type boat comprising a plurality of frames provided with elongated longitudinal openings substantially coextensive with the central portion of the frames, the openings in the respective frames being in alignment, continuous longitudinal stringers projecting through said openings and interlocked with said frames to form a substantially rigid framework, and a boat shell covering the exterior of said framework, said shell having integral side members, an integral bottom member meeting said side members at a chine line, an integral stern member, and a

floor member located in the lower portion of said boat and supported by the boat framework.

6. An open type boat comprising a framework formed of a plurality of frames provided with elongated longitudinal openings substantially coextensive with the central portion of the frames, the openings in the respective frames being disposed in alignment, continuous longitudinal stringers projecting through said openings and interlocked with said frames to form a reticulated substantially rigid structure, a boat shell covering the exterior of said framework, said shell comprising integral side members extending from the gunwales to the chines, bottom members extending from the chines to bottom chines, a continuous bottom member extending between said bottom chines, an integral stern member, and a floor supported by and substantially covering the lower interior of said framework.

7. In a boat, a plurality of square frames provided with elongated longitudinal openings substantially coextensive with the central portion of the frames, the openings in the respective frames being disposed in alignment, a plurality of longitudinal stringers projecting through said openings and attached to said frames at their intersection therewith, a boat bottom and a boat floor, so arranged that the bottom portion of the boat approximates a box beam.

8. A boat bottom construction comprising a plurality of frame members provided with elongated longitudinal openings substantially coextensive with the central portion of the frame members, the openings in the respective frame members being disposed in alignment, a plurality of longitudinal stringers projecting through said openings and interlocked with said frames at their intersection therewith, a shell bottom member covering the underside of said interlocked structure, and an inner floor supported by the top side of said interlocked structure.

9. In a boat, a plurality of substantially channel shaped frames provided with elongated longitudinal openings substantially coextensive with the central portion of the frames, the openings in the respective frames being disposed in alignment, a plurality of continuous longitudinal stringers projecting through said openings and interlocked with the bottom portions of said frames to form a reticulated structure, a shell bottom member covering the underside of said reticulated structure and being attached thereto, and an inner floor supported by, attached to and substantially covering the top portion of said reticulated structure.

10. In a boat, a plurality of transverse frames provided with elongated longitudinal openings substantially coextensive with the central portion of the frames, the openings in the respective frames being disposed in alignment, a plurality of longitudinal stringers projecting through said openings, a bottom and a floor secured along the opposite sides of said frames and stringers, so arranged to form a box beam structure, and side-walls carried by said box beam structure defining a boat.

11. A boat of the character described comprising a bottom, side members, a transom and a floor united by an inner reticular framework, said framework including a plurality of longitudinally spaced, parallelly arranged, transverse frames, said frames comprising a lower horizontal portion provided with a longitudinally extending opening, and adapted for the attachment of the bottom and floor, and upwardly extending frame

portions for the attachment of the side members, and longitudinal stringers provided with correspondingly located notches on the upper and lower edges thereof, said stringers being adapted to be turned sideways and slipped through the openings in said transverse frames and turned upright therein for engagement of said notches by the upper and lower edges bordering the longitudinal opening, and reinforcing battens uniting the said frames and said stringers at their intersections to form a rigid reticular structure.

12. A boat of the character described comprising a bottom, side members, a transom and a floor, an inner reticular framework spaced intermediate said bottom and said floor to form a box beam structure, said framework including a plurality of longitudinally spaced, parallelly ar-

ranged, transverse frames, said frames comprising a lower horizontal portion, provided with a longitudinally extending opening, and adapted for the attachment of the bottom and floor, and lateral upwardly extending frame portions for the attachment of the side members, and longitudinal stringers provided with correspondingly located notches on the upper and lower edges thereof, said stringers being adapted to be put through the openings in said transverse frames and turned upright therein for engagement of said notches by the upper and lower edges bordering the longitudinal opening, and reinforcing battens uniting the said frames and said stringers at their intersections to form a rigid reticular structure.

CARL H. CLEMENT, JR.
